Primary Examiner — Richard E Chilcot(74) *Attorney, Agent, or Firm* — Fish & Richardson P.C.**CLAIM**

The ornamental design for an autonomous transport robot, substantially as shown and described.

DESCRIPTION

FIG. 1.1 is a front view of an autonomous transport robot, showing my new design;

FIG. 1.2 is a left side view thereof;

FIG. 1.3 is a rear view thereof;

FIG. 1.4 is a right side view thereof;

FIG. 1.5 is a top view thereof;

FIG. 1.6 is a bottom view thereof; and,

FIG. 1.7 is a front top-left perspective view thereof.
